US00D852760S

(12) **United States Design Patent** (10) **Patent No.:** **US D852,760 S**
Hoffknecht et al. (45) **Date of Patent:** **** Jul. 2, 2019**

(54) **SWITCH**

(71) Applicants: **Marc Hoffknecht**, Newmarket (CA);

Simon Treadwell, Toronto (CA);

Sabolch Feigler, Mississauga (CA);

Marian Kosara, Pickering (CA)

(72) Inventors: **Marc Hoffknecht**, Newmarket (CA);

Simon Treadwell, Toronto (CA);

Sabolch Feigler, Mississauga (CA);

Marian Kosara, Pickering (CA)

(73) Assignee: **OSRAM SYLVANIA Inc.**, Wilmington, MA (US)

(**) Term: **15 Years**

(21) Appl. No.: **29/639,836**

(22) Filed: **Mar. 9, 2018**

Related U.S. Application Data

(62) Division of application No. 29/558,570, filed on Mar. 18, 2016, now Pat. No. Des. 819,577, which is a division of application No. 29/492,292, filed on May 30, 2014, now Pat. No. Des. 781,247.

CLAIM

The ornamental design for a switch, as shown and described.

DESCRIPTION

FIG. 1 is a perspective view of an embodiment of the ornamental design of the switch.

FIG. 2 is a front view of an embodiment of the ornamental design of the switch.

FIG. 3 is a top view of an embodiment of the ornamental design of the switch.

FIG. 4 is a bottom view of an embodiment of the ornamental design of the switch.

FIG. 5 is a side view of an embodiment of the ornamental design of the switch.

FIG. 6 is a perspective view of an embodiment of the ornamental design of the switch; and,

FIG. 7 is a front view of an embodiment of the ornamental design of the switch.

(Continued)

The broken-line disclosure in the views is understood to represent portions of the article in which the claimed design is embodied, but which form no part of the claimed design.

1 Claim, 6 Drawing Sheets
